UNITED STATES PATENT OFFICE.

ARTHUR B. MODINE, OF RACINE, WISCONSIN.

TUBULAR RADIATOR CORE.

Application filed January 2, 1920. Serial No. 348,989.

To all whom it may concern:

Be it known that I, ARTHUR B. MODINE, a citizen of the United States, residing at Racine, in the county of Racine and State 5 of Wisconsin, have invented certain new and useful Improvements in a Tubular Radiator Core, of which the following is a description.

My invention relates to coolers or condensers of the kind employed for controlling the temperature of automobile motors and the like for bringing the fluid to be cooled into the most intimate relation possible with the cooling fluid.

10 The object of my invention is to provide a light, simple, strong, reliable and highly efficient device of the kind described, wherein in the entire surface of both sides of the walls of the cooling channels are exposed in order to secure the maximum transmission 20 of heat to the cooling fluid.

To this end my invention consists in the novel construction, arrangement and combination of parts herein shown and described and more particularly pointed out in the claim.

In the accompanying drawings wherein like or similar reference characters indicate like or corresponding parts:

30 Fig. 1 is a perspective view of a portion of a radiator core embodying my improvement.

Fig. 2 is a perspective view of a channel and a spacer in their respective vertical position but separated slightly laterally to more clearly show the construction and relation of the parts.

Fig. 3 is a perspective view showing two channels and a slightly modified form of 40 spacer arranged as shown in Fig. 2.

Fig. 4 is a front elevation of a portion of a radiator showing another modified form of spacer.

Fig. 5 is a section taken substantially on 45 line 5—5 of Fig. 4.

Fig. 6 is a front elevation of a portion of a radiator showing another modified form of spacer.

Fig. 7 is a perspective view of the spacer 50 shown in Fig. 6.

Fig. 8 is a front elevation of a portion of a radiator showing yet another modified form of spacer.

Fig. 9 is a perspective view of the spacer 55 shown in Fig. 8.

In the form shown my improved radiator

core comprises a plurality of substantially vertical zig zag tubes or channels suitably spaced from each other and with a plurality of spacing members extending between the tubes preferably between the apexes of the adjacent bends or corrugations of the tubes the whole being connected by soldering, brazing or other suitable means for permanently securing the several parts in position.

In the form shown each tube comprises a pair of substantially similar strips 1 of suitable material having an off-set 2 near each edge and a fin or margin 3 projecting beyond the off-set portion so formed that when the strips are brought together back to back, the margins will contact throughout their length and width affording a convenient method of permanently connecting 75 the strip by solder or other convenient means to produce a fluid tight tube.

In the preferred construction the tubes are corrugated or plicated transversely, the angle of the adjacent corrugations being 80 preferably 120 degrees so that when assembled with similar tubes and suitably spaced the apexes of the adjacent angles of the tubes may be connected thus forming a succession of substantially hexagonal spaces at 85 each face of the radiator core.

Any suitable means may be provided for connecting the several tubes and rigidly holding them in position. In the form shown in Figs. 1 and 2 the spacer 4 comprises a strip of suitable material corresponding in width to the width of the projecting fin or margin 3 bent upon itself as at 5 and with the ends 6 and 7 bent outward to fit against the fin on the respective sides of one of its angles, the parts 6 and 7 being of sufficient length to reach to the next adjacent angle of the fin while the end 5 of the spreaders engages the apex of the fin of the next adjacent tube, thus accurately maintaining the parts in position as shown in Fig. 1. In this form shown also the surfaces of the tubes are each roughened or checkered in any suitable or convenient manner, such for example as by small corrugations or indentations formed in the tube walls to increase the radiating surface of the tubes and also to increase the turbulence of the air passing between the tubes thereby increasing the transmission of heat from 110 the fluid passing through the tubes to the air passing between them.

- In the form shown in Fig. 3 the spacer 8 comprises a single strip corresponding in width to the width of the co-operating fin and successively bent as shown at 9, 10 and 11 thus providing a portion 12 adapted to bear against one of the angular faces of the fin, a part 14 extending from the apex of the angle of the fin upon one tube to the apex of the angle of the fin of the next adjacent tube and a part 15 formed to bear against the angular faces of the fin of the next adjacent tube, these angles and parts being successively repeated through the height of the radiator.
- In the form shown in Figs. 4 and 5 the spacers 16 are formed substantially as shown in Figs. 1 and 2 except that the several spacers for each pair of tubes is formed in a single strip extending from the top to the bottom of the radiator and bent in the same general way to form the distance pieces 17, 18 and 19 as shown in detail in Fig. 2.
- In the form shown in Figs. 6 and 7 the spacer 20 corresponds to the form shown in Fig. 3 except that a succession of separate spacers 20 are provided in place of the strip of connected spacers as shown in Fig. 3. The general form of the spacer 20 however remains substantially the same, that is, the parts 21, 22 and 23 correspond to the parts 12, 14 and 15 respectively.
- In the form shown in Figs. 8 and 9 the spacer 24 is formed of two pieces of suitable width rigidly connected as by a rivet 25 and with the ends 26 and 27 of each piece bent outward at each end as shown, adapted to bear against the angular faces of the fins of the adjacent tubes as shown in Fig. 8 to hold the tubes in position. In each case the spacers are preferably assem-

bled with the several pairs of plates comprising the tubes and all soldered or brazed at a single operation thus firmly and positively uniting the several parts of my improved radiator core without in any manner interfering with or filling the roughened portion of the tubes. While in the accompanying drawings I have shown my improved radiator arranged to produce a hexagonal cellular appearance at each end, it is obvious that the form or arrangement of tubes and spacers can be altered in various ways to produce other forms or configurations without departing from the spirit of my invention, hence, I do not wish to be understood as limiting myself to the exact form or construction shown.

What I claim as new and desire to secure by Letters Patent is:

A radiator core comprising a plurality of tubes each comprising a pair of alternately bent zigzag plates united in parallel to form zigzag tubes each tube provided with a zigzag projecting fin extending along each side centrally of the opposed walls of said tube, said tubes spaced apart so that the opposed surfaces of adjacent tubes are inclined relatively of one another throughout their height, in combination with a plurality of independent separately formed spacers each of a width equal to the width of said fins and positioned between the fins of adjacent tubes and bearing thereagainst from the apex of a fin to its base to space said tubes apart to form a continuous air space therebetween throughout their opposed areas, said air space varying in size throughout its vertical extent.

In testimony whereof, I have hereunto signed my name.

ARTHUR B. MODINE.
